UNITED STATES PATENT OFFICE

153,242

DESIGN FOR A CUTTING TABLE FOR
YARD GOODSWilliam L. Stensgaard, Park Ridge, Ill., assignor
to Goodall-Sanford, Inc., a corporation of
Maine

Application January 6, 1948, Serial No. 143,566

Term of patent 14 years
(Cl. D80—9)*To all whom it may concern:*

Be it known that I, William L. Stensgaard, a citizen of the United States, residing at Park Ridge, in the county of Cook and State of Illinois, have invented a new, original, and ornamental Design for a Cutting Table for Yard Goods, of which the following is a specification reference being had to the accompanying drawing forming a part thereof.

Fig. 1 is a side elevational view of a cutting table for yard goods showing my new design;

Fig. 2 is a top plan view;

Fig. 3 is an end elevational view; and

Fig. 4 is a fragmentary sectional view of one end thereof.

I claim:
The ornamental design for a cutting table for yard goods, as shown.

W. L. STENSGAARD.
